(Cl. D56—4)

FIG. 1.

FIG. 2.

FIG. 3.

FIG. 4.

FIG. 5.

FIGURE 1 is a perspective view of a combined table and high fidelity cabinet showing my new design, and showing the same with the doors of the cabinet in their respective closed positions;

FIGURE 2 is a perspective view thereof, similar to FIGURE 1, FIGURE 2 showing the doors of the cabinet in their open position;

FIGURE 3 is a front elevational view thereof;

FIGURE 4 is an end elevational view thereof; and

FIGURE 5 is a detail front sectional view thereof, FIGURE 5 being taken substantially on the vertical plane of line 5-5 of FIGURE 3, looking in the direction of the arrows.

The end of the unit not shown is like the end shown

while the back of the cabinet and speakers are plain and unornamented.

I claim:

The ornamental design for a combined table and high fidelity cabinet, as shown and described.
